(57) **CLAIM**

The ornamental design for a vehicle repair seat, as shown and described.

DESCRIPTION

FIG. 1 is a perspective view of a vehicle repair seat showing my new design;

FIG. 2 is a top view of the vehicle repair seat shown in FIG. 1;

FIG. 3 is a bottom view of the vehicle repair seat shown in FIG. 1;

FIG. 4 is a left side view of the vehicle repair seat shown in FIG. 1; and,

FIG. 5 is a front side view of the vehicle repair seat shown in FIG. 1.

The broken lines in the figures shown portions of the vehicle repair seat, which form no part of the claimed design.
